SIGNAL CONTAINER

Filed April 24, 1929

INVENTOR.
Henry H. Landess.
BY Chas. Gerard,
ATTORNEY

UNITED STATES PATENT OFFICE

HENRY H. LANDESS, OF PRATT, KANSAS

SIGNAL CONTAINER

Application filed April 24, 1929. Serial No. 357,712.

The present invention relates to containers or receptacles, and particularly to the special form of container which is designed for use in the carrying of signal supplies of the general type used in railway signaling.

Accordingly, the primary object in view is to devise an improved type of receptacle for preserving a portable supply of signaling materials as required for both day and night signal operations.

Incidentally it is sought to provide an improved construction which will safely preserve the materials from deterioration and against loss or misplacement, and maintain a convenient supply of such materials readily accessible at all times for instantaneous use.

Another incidental object of the invention is to provide a container having an improved form of carrying means including an improved feature in the cover retaining structure.

With the foregoing general objects in view as well as various other minor objects as will appear in the course of the following detailed specification, the invention will now be described by reference to the accompanying drawing illustrating one form of embodiment of the invention, after which those features and combinations thereof deemed to be novel 30 will be set forth and duly claimed.

In the drawing—

Figure 1 is an exterior plan view of a container or receptacle constructed in accordance with my present invention;

Figure 2 is a longitudinal sectional view, on a larger scale;

Figure 3 is an end view; and

Figure 4 is an end view, with one of the cover members removed.

Referring now to the drawing in detail, the improved container construction is illustrated as comprising a cylindrical body portion 10 formed of any suitable sheet metal, and in any appropriate size, and provided near its opposite ends with exterior beads 12 adapted to reinforce the shell comprising the body, and also serving as weatherproofing stops for the end covers or cap pieces 14 which serve as closure members for the open ends of the container. These cover or closure members 14

are fitted with suitable handle loops 16 swivel-mounted on their outer or end faces (see Figure 3), and for abutting engagement with the beads 12 the cover members are formed with marginal rolls or beads 17 each enclosing a band of reinforcing wire; and each roll or bead has an open section exposing a portion of the wire which is formed into a strap loop 18. Adjacent to each of the beads 17 is also secured a strap loop or keeper element 20 at the exterior of the body 10 of the container,—the two loops or keeper elements 20 being in alinement and designed for the passage of a flexible carrying strap 21, or chain or the like, provided with an adjustable fastening, such as a buckle 22.

With this construction it is apparent that the cover members 14 may be turned to bring the loops 18 in line with the loops or keeper elements 20 for facilitating the continuous passage of the strap 21, which thus serves both to secure the cover members in closed position over the ends of the container body and also as a carrying means for the container; at the same time the strap is sufficiently long to permit either cover member to be removed when necessary to afford access to the contents of the container, and still maintain connection between the cover and body of the container.

Moreover, the length of the strap may be such as to allow use of the same as either a shoulder strap, or to be caught up in the form of a shorter hand strap or grip, as illustrated in Figures 1 and 2.

Intermediate the exterior beads 17, the body 10 of the container is also formed with a pair of spaced intermediate beads 25 also serving to reinforce the body and also acting as stops against which rest a pair of partition elements 26 and 27, respectively, as shown in Figure 2. The partition element 26 divides the interior of the container body into a relatively shallow compartment 28 for storing a supply of torpedoes 29 or the like, and a relatively larger compartment 30 for storing a supply of fuses 32. The partition member 27 is accordingly provided with an annular series of openings 33 for receiving and maintaining the fuses 32 in separated and

substantially parallel relation within the compartment 30, and with their inner ends resting against the partition member 26.

Also mounted substantially axially within the container compartment 30 is a tube 35 extending through the centers of both partition members and projecting part way through the smaller compartment 28 where the end of the tube is closed. The tube 35 is suitably secured to both of said partition members, and is designed to carry a signal flag 36 with its staff conveniently accessible on opening the cover member to the compartment 30.

It is thus apparent that a strong, compact and durable form of container is provided for maintaining a convenient and readily accessible supply of the usual signal materials required to be on hand for either day or night use. Obviously the contents are practically instantly accessible by simply removing either or both of the cover members 14, and the strap device 21 functions not only as a securing means for holding both cover members in closed position but also as a retaining means for keeping the parts connected together even while the cover members are separated from the ends of the body portion 10. This method of connecting the parts eliminates the use of latches, hinges or the like, and the described construction moreover involves no irregular or angular parts or projecting corners such as would be apt to catch or snag the clothes in any way. Being of round and cylindrical form, it is evident that the construction is exceptionally strong and durable, the interior partition members also serving to reinforce the body of the container, and these partitions in turn are connected, and braced and reinforced by the provision of the flag tube 35 secured thereto.

The use of the improved container or receptacle is well adapted not only for locomotive engines as an accessory thereto, but also for other points or locations wherever it is important or desirable to maintain a convenient supply of the signal materials on hand,—including way stations, or other service points, as well as on hand cars, motor cars, and so forth, where the equipment may be conveniently installed in readiness for instant use. The character of the container construction is such that the supplies are kept in a perfectly dry and efficient condition, substantially sealed against moisture or other deteriorating influences, and the loss or misplacement, as well as misuse, of the parts is prevented.

The signal materials are, moreover, kept all together in compact form, rather than in a promiscuous disorderly fashion as has been common practice,—thus making for both economy and safety in the handling and storing of such supplies.

While I have illustrated and described

what I now regard as the preferred form of embodiment of my improvements, I desire to be understood as reserving the right to make all such changes or modifications as may fairly fall within the scope of the following 70 claims.

Having thus described my invention, what I claim as new and desire to secure by Letters-Patent, is:

1. A signal material container comprising 75 a cylindrical body open at both its ends, a cover member removably applied to each end of said body, loop elements carried by said body and cover members, and a single flexible carrying strap slidingly connected with said 80 loop elements of both body and cover members for permitting manipulation of the cover members into open relation to the body while maintaining the connection between them and said body.

2. A signal material container comprising 85 a cylindrical body open at both its ends, separate spaced partition elements dividing the interior of the body into separate compartments, and a flag receiving tube supported 90 by the central portions of said partition elements in axial relation to said body.

3. A signal material container comprising 95 a cylindrical body open at both its ends, separate spaced partition elements dividing the 100 interior of the body into separate compartments, a flag receiving tube supported by the central portions of said partition elements in axial relation to said body, one of said partition elements having a plurality of spaced 105 openings surrounding said tube, and a cover member removably applied to each end of said body.

4. A signal material container comprising 110 a cylindrical body open at both its ends and provided with a pair of spaced circumferential beads, a pair of partition elements dividing the interior of the body into separate compartments, a flag-receiving tube supported by the central portions of said partition 115 elements and securing the same in abutting engagement with said beads, respectively, and a cover member removably applied to each end of said body.

5. A signal material container comprising 115 a cylindrical body open at one of its ends, a cover member removably applied to said open end of the body and formed with a marginal roll or bead, a reinforcing wire enclosed by said marginal bead and having an exposed 120 strap loop portion, alined strap loop elements carried by said body, and a flexible carrying strap extending continuously through the strap loop elements of both said body and said cover member.

6. A signal material container comprising 125 a cylindrical body open at both its ends, a cover member removably applied to each end of the body and formed with a marginal roll or bead, a reinforcing wire enclosed by the 130

5 marginal roll or bead of each of said cover members and having an exposed strap loop portion, alined strap loops carried by said body, and a flexible carrying strap extending continuously through the strap loop elements of both said body and cover members and adapted to permit independent manipulation of the cover members into open relation to the body while maintaining the connection between them and said body of the container.

10 In witness whereof I hereunto affix my signature.

HENRY H. LANDESS.
